Des. 233,806
Patented Dec. 3, 1974

233,806

BRUSH

Hiroshi Hukuba, Nagareyama, Japan, assignor to Kabushiki Kaisha Hukuba Future Research, Nagareyama, Japan

Filed July 27, 1973, Ser. No. 383,400

Term of patent 14 years

Int. Cl. D4—01

U.S. Cl. D4—12

Fig. 1

FIG. 1 is a perspective view of a brush, shown attached to a carpet sweeper, which carpet sweeper is shown in broken lines for illustrative purposes only and forms no part of the claimed design;

FIG. 2 is a side elevational view of the brush;

FIG. 3 is a left edge view of the brush illustrated in FIG. 1;

FIG. 4 is a right edge view of the brush illustrated in FIG. 2;

FIG. 5 is a top view; and

FIG. 6 is a bottom view.

I claim:

The ornamental design for a brush, as shown and described.
